UNITED STATES PATENT OFFICE.

ISAAC P. RODMAN, OF NEWARK, NEW JERSEY, ASSIGNOR, BY MESNE ASSIGNMENTS, TO GAROD CORPORATION, OF BELLEVILLE, NEW JERSEY, A CORPORATION OF NEW JERSEY.

WIRELESS RECEIVING TUNER.

Application filed February 1, 1922. Serial No. 533,377.

To all whom it may concern:

Be it known that I, ISAAC P. RODMAN, a citizen of the United States, residing at #558 Central Avenue, in the city of Newark, 5 in the county of Essex and State of New Jersey, have invented a new and useful Wireless Receiving Tuner, of which the following is a specification.

My invention relates to improvements in 10 wireless receivers, in which a crystal detector and condenser connected in series are conductively coupled to the primary circuit and in which the primary circuit inductance is adjusted by varying the relative positions 15 of two helical coils, and the objects of my improvements are first—to provide a compact, pocket size, wireless tuner, and second—to afford facilities for adjusting the values of inductance.

20 I attain these objects by the apparatus illustrated in the accompanying drawings in which—

Figure 1 is a perspective view, the box being open and parts being broken away.

25 Fig. 2 is a bottom plan view of a movable inductance member.

Fig. 3 is an end view of the member of Fig. 2.

Fig. 4 is a plan view, on a reduced scale, 30 of a part of the device, showing the fixed cooperating inductance member.

Fig. 5 is an end view of the part shown in Fig. 4, and

Fig. 6 is a diagram of the wiring of the 35 instrument.

Similar reference characters refer to similar parts throughout the several views.

The circuits of my receiver are mounted upon and in a small compact box, which 40 is of pocket size, the dimensions being of an order to fit in an ordinary pocket, and which comprises two parts, A and B, connected by the metal hinges E, F, one part A being the box proper and the other part B 45 being the cover. The parts may be closed and secured together by means of a hook N adapted to engage a pin or screw o.

The receiver, such as I have herein disclosed to illustrate an embodiment of my 50 invention, usually comprises, an inductance, condenser, detector and the connected circuits adapted to efficiently receive and make audible the electro-magnetic impulses received. My invention includes the arrangement 55 of these devices within the casing or

box and with reference to each other, so that the whole device is compact, will be easy to operate, and may be completely enclosed when not in use.

For this purpose I mount a portion of the 60 electrical devices of the circuit on one part of the box and the remainder of the electrical devices on the other part. It is immaterial in which part any particular device is located. All that is necessary is that 65 the several devices be so arranged on their respective parts that they do not interfere with each other to prevent the closing of the box.

To illustrate one embodiment of the invention in the accompanying drawings I show an inductance D G mounted on one part, as here illustrated, in the part A or box proper, and the condenser P and detector Q mounted on the other part B or 70 upon the inner side of the cover.

The inductance members or devices D G are mounted to slide rectilinearly relatively to each other on the part A. Each inductance member comprises a flat helical or spiral coil of insulated wire in which the successive convolutions are very close together. The coil D is mounted upon the bottom of part A near one end, and can be secured thereto in any suitable manner, as 75 by a suitable adhesive or glue. The coil G is in like manner secured to one side of a blocklike mounting C in such position thereon that the center of the coil coincides with the point of intersection of the diagonal 80 lines drawn from the corners of the block C. The part of the box on which the inductances are mounted are provided with parallel guideways U V which are illustrated in this embodiment of the invention as formed in the side pieces H and I of the box A, one 85 end of the box A being open or unobstructed to allow the insertion and removal of the coil G and its mounting C into and out of the guideways or grooves U V. This arrangement provides means for variably sliding one coil member over the other to vary 90 the inductance of the circuit and hence the wave length adjustment, the coil G facing the coil D and being fairly close thereto to secure close coupling and to permit the use of a very small box. The mounting C 95 has secured to it upon opposite sides slide contacts L M, consisting of springy strips of metal, the contact L being electrically con-

nected by a conductor 6 to the outside of coil G and the contact M being electrically connected by a conductor 5 to the center of coil G. The contacts L and M engage 5 and slide over parallel metal pieces or strips K J, fastened in the bottom of the box A at opposite sides near the guideways U V, and remain in contact therewith in all positions of the coil G relative to coil D, either 10 in the right hand position shown in Fig. 1 or stopped at the extreme left, looking at Fig. 1, forming sliding contacts between the movable coil G and the fixed parts of the receiving circuit. The coil D is so 15 mounted, that, when the mounting C is flush with the open end of the side pieces H I, the coils will be in maximum overlapping position with their centers coinciding. The condenser P and detector Q are secured to 20 the part B, upon its inner surface but at the end thereof remote from the inductance D (and also mounting C, if the latter is at the right as shown in Fig. 1), so that when the parts A and B are closed the electrical 25 devices will not interfere but will occupy different portions of the box, thereby providing a compact and completely enclosed unit, the cover B being provided with a vertical strip at its right hand end (Fig. 1) 30 adapted to cooperate with strips or sides H I to complete the enclosure and cover the open end of box A.

Any type of suitable detector may be employed in this invention, such for instance 35 as a crystal. I have however illustrated a specific form of crystal detector Q which is especially adapted for a portable pocket set of the present character and which is reasonably immune to shocks, blows or vibrations.

40 This detector comprises a crystal of any suitable character now well known, suitably mounted, as for instance in a metal and a flexible wire R in the circuit of the receiver, secured at one end by a screw S and having a free end which can be moved to 45 engage the surface of the crystal at different points to find a sensitive place, the wire by reason of its flexibility and springiness allowing this adjustment and providing a firm 50 pressure on the crystal. The wire R is preferably of bare soft drawn copper having a diameter not exceeding 3/64 inches and of a length approximately 2 inches. Because of its light weight and low value of 55 inertia, the wire when once located remains in position and is not susceptible to shocks, blows, etc.

Spring clip terminals or binding posts T¹, T², T³ and T⁴ are secured to the inner side 60 of the cover B in such position as not to interfere with the closing thereof. The terminal T¹ is for the antenna lead, the terminal T² for the ground lead and the terminals T³ and T⁴ for the phone or amplifier 65 leads.

The circuits of the receiver are completed through the several electrical devices as follows. The crystal Q is electrically connected to the antenna terminal T¹ by a conductor 1. The crystal Q is connected to the inner end 70 of inductance coil D through conductor 2, mounted on part B, hinge E and conductor 3, mounted on part A, the oposite end of coil D being electrically connected to strip K by conductor 4. The other strip J is electrically connected to hinge F by conductor 7 mounted on box A and hinge F is electrically connected to ground terminal T² through conductor 8. The wire R is electrically connected by a conductor 9 to one terminal of the condenser P, this terminal of the condenser being electrically connected to the telephone clip T⁴ by a lead 10 and the opposite terminal of the condenser being electrically connected to the other phone clip T² 85 by a lead 11. The circuit through coils D and G may be traced from hinge E, through coil D to strip K, from strip K and contact M through coil G to contact L and strip J and from there to hinge F. By reason of 90 the construction and connections above described the flow of current through the coils is in opposite directions (although they may be in the same direction) and hence (when connected as shown) they inductively oppose each other, like a variometer, the circuit having minimum inductance when the coils are in maximum overlapping position and maximum inductance when the coil G is at the extreme left (Fig. 1), thereby varying the 100 wave length adjustment from minimum to maximum.

105 The circuits are also illustrated in Fig. 6 and form what are known in the art as the primary and secondary circuits. The primary circuit includes the inductance D G and the secondary circuit includes the detector Q, condenser P, if used, and telephones.

110 By removing mounting C and reversing its position so that contact M engages strip J and contact L engages strip K, the direction of flow of current is reversed in coil G so that the inductances of the circular or pancake coils add as they approach each other thereby securing an increased range of 115 wave length adjustment.

120 Coil mounting C may be removed from the instrument and other coil mountings applied, which other coil mountings may have 125 value of inductance different from each other making it possible for the instrument to have variable inductance values over a wide range. It is possible by providing additional grooves U and V and additional coil mountings C to apply an inductive variable coupling between the primary and secondary circuits.

I claim:

130 1. A device of the character described comprising a support having an extended

surface, flat coils thereon relatively movable laterally over the faces of each other into and out of overlapping relation and having areas compared to that of said supporting surface such as to maintain 40 said coils in parallelism in each position without projecting beyond the edges of said support; said coils being arranged to be either increasingly additive in their inductive effects or increasingly opposing in their 45 inductive effects, as desired, upon relative movement thereof, and a member associated with said support and adapted to enclose said coils; said support and said member constituting an enclosure 50 serving, when in closed relation, to maintain said coils within the confines of said support and prevent the removal thereof.

2. A device of the character described comprising a support, a flat coil mounted on said support at one end thereof, parallel 55 conducting and guiding members mounted on said support at opposite sides of said coil and extending beyond the same, a slideable supporting member, a flat coil thereon facing said first named coil, contacts carried by said 60 supporting member and slidably engaging said conducting members; said contacts maintaining an electrical connection between said coils in the different relative positions thereof, and a member associated with said 65 support and adapted to enclose said coils and serving, when in closed position, to maintain said coils within the confines of said support and prevent the removal thereof.

3. A device of the character described comprising a support having an extended 70 surface, a plurality of flat coils thereon relatively movable laterally over the faces of

each other into and out of overlapping relation and having areas compared to that of said supporting surface such as to maintain 40 said coils in parallelism in each position without projecting beyond the edges of said support; said coils being arranged to be either increasingly additive in their inductive effects or increasingly opposing in their 45 inductive effects, as desired, upon relative movement thereof, and a member associated with said support and adapted to enclose said coils and serving, when in closed position, to maintain said coils within the 50 confines of said support and prevent the removal thereof.

4. A device of the character described comprising a support, a flat coil thereon at one end thereof, parallel guiding and conducting members mounted on said support at opposite sides of said coil and extending beyond the same towards the opposite end of said support, a slideable supporting block, a flat coil upon the side thereof facing said 60 first named coil, spring contacts on said block slidably engaging said conducting members to maintain said coils electrically connected in series in the different positions thereof; said block being movable in said 65 guiding members and on said support into and out of overlapping relation to said first named coil without projecting beyond the edges of said support, and a member carried by said support for enclosing said coils and 70 serving, when in closed position, to maintain said coils within the confines of said support and prevent the removal thereof.

ISAAC P. RODMAN.
